(57) **CLAIM**

The ornamental design for a label recess portion of a bottle, as shown and described.

DESCRIPTION

FIG. 1 is a perspective view of a label recess portion of a bottle according to our new design;

FIG. 2 is a front elevation view thereof;

FIG. 3 is a left side elevation view thereof, the right side elevation view being a mirror image;

FIG. 4 is a back elevation view thereof;

FIG. 5 is a top plan view thereof;

FIG. 6 is a bottom plan view thereof; and,

FIG. 7 is a cross-section view taken along line 7—7 as shown in FIG. 2, shown at an enlarged scale.

The broken lines shown in the drawings are for environmental purposes only and form no part of the claimed design.
